UNITED STATES PATENT OFFICE.

LEWIS ASPER, OF MINNEAPOLIS, MINNESOTA.

STORM-SASH HOLDER.

Application filed March 17, 1927. Serial No. 176,003.

This invention relates to holding devices for swinging sash and especially to storm sash holders.

It is the main object of the invention to provide a simple, inexpensive, durable and highly efficient holder for swinging sash adapted to fasten the swinging sash in fully open position and also adapted to securely hold the same in closed position or in positions intermediate said closed and open positions.

A further object of the invention is to provide a swinging storm sash holder, including toggle arms affixed to the swinging sash and a simple bracket permanently secured to a portion of the window frame, whereby said swinging sash may be readily attached and said holder properly secured to said bracket for operation without installation of parts.

Another object is to provide in a storm sash holder, means to prevent the storm sash from rattling at its point or points of connection with the holder proper.

These and other objects of the invention will be apparent from the following description made in connection with the accompanying drawings, in which like reference characters refer to similar parts throughout the several views and in which:—

Fig. 1 is a vertical cross section through a lower portion of a storm sash and window frame showing a preferred embodiment of my device attached thereto in operative position, an intermediate position of said storm sash being shown in dotted lines;

Fig. 2 is a similar view showing said storm sash in closed position;

Fig. 3 is a vertical section taken on the line 3—3 of Fig. 2;

Fig. 4 is a perspective view of the attaching bracket employed on the window frame; and

Fig. 5 is a perspective view of a substantial portion of the inner arm employed in my holder.

In the drawings, the sill of the window frame is indicated by the numeral 6 and the vertical sides of said window frame by the numeral 7. The usual spaced sash stops 8 are provided on the vertical sides 7 between which the upper sash of the window is guided. A swinging sash, illustrated in the drawings, as a storm sash is pivoted to the

upper portion of a window frame (not shown) and its lower horizontal rail or frame member is indicated by the numeral 9.

My sash holder when the swinging sash is detached is carried thereby and may be secured thereto by means of a bracket 10 having a vertical flange disposed at right angles to the surface of rail 9. An outer arm 11, of preferably flat material is pivoted at its outer end to said flange or bracket 10 and has a lower longitudinally recessed portion 11^a formed at its lower longitudinal edge affording a small bell crank lever arm 12 in connection with the pivot 13 securing said arm to said flange. Arm 11 forms one of a pair of toggle arms and is pivoted at 14 to the other arm 15 of said pair. Arm 15 may be of substantially rectangular shape having a key hole slot 15^a formed adjacent its inner end, which slot is adapted to receive the head 16^a of a pivot member projecting longitudinally and substantially horizontally from the end of an angle bracket 17. Angle bracket 17 is preferably secured to a vertical wall 7 of the window frame between the sash stops 8, said pivot or lug extending towards the opposite side of said window frame.

Arm 15 is pivotally attached to bracket 17 by inserting the head 16 of said pivot into the key hole slot 15^a, slipping arm 15 inwardly slightly and swinging a retaining arm 18 downwardly to permit the pivot 16 to be engaged by an arcuate slotted portion 18^a adjacent the free end of arm 18. This, obviously, prevents the headed portion 16^a of said pivot from slipping out of said key hole slot. Arm 18 is pivoted intermediately of arm 15 on a threaded bolt 19 provided with a winged clamping nut 20. It will be noticed that the unthreaded end of bolt 19 extends through arm 15 and forms a lug 19^a, best shown in Fig. 3, which is adapted to lock with a detent 21 formed in the lower edge of arm 11 adjacent its inner end. Thus, when the storm sash is in fully open position, toggle arms 11 and 15 will be substantially aligned and detent 21 will be engaged by said lug 19^a.

The operation of the above described device may be briefly summarized as follows:

When the storm sash is closed the several elements will be positioned, as shown in Figs. 2 and 3, the lower edge or rail 9 being engaged by the sill 6 and toggle arms 11 and 15

being positioned in nearly coincident relationship. The elongated recessed portion 11^a of toggle arm 11 accommodates the projecting arms 19^a disposed intermediately of the 5 ends of toggle link 15 when the storm sash is in closed position. Sufficient friction is afforded between the contacting surfaces of arms 11 and 15 to prevent the storm sash from swinging outwardly. To fully open 10 the storm sash it is only necessary to apply pressure against the inner side thereof causing toggle arms 11 and 15 to be swung apart and disposed in alinement, as shown in Fig. 1, detent 21 fastening with lug 19^a and positively preventing said arms from displacement by wind. It will also be noticed that as the arms are swung apart the bell crank arm 12 formed at the outer end of arm 11 will be cammed or forced against the base of 15 bracket 10 thereby taking up any looseness between the pivot 13 and arm 11 and preventing rattling of said storm sash.

The storm sash may be held in various positions intermediate of said closed position and 20 said open position by the friction between arms 11 and 15 and in Fig. 1 the dotted lines indicate said storm sash held in intermediate position.

It will be seen that in detaching the storm 25 sash from the window frame it is only necessary to loosen wing nut 20, swing arm 18 upwardly and remove pivot 16 from key hole slot 15^a. The toggle arms, bracket 10 and all elements of the sash holder with the exception 30 of bracket 17, are carried by the storm sash and are removed with said sash. Bracket 17, of course, does not interfere with the sashes in the window frame, since it is preferably disposed between the stops 8 for the upper 35 sash and since there is no occasion for lowering the upper sash of the window to such extent that the lower edge thereof will abut bracket 17.

In many forms of storm sash holders on the 40 market the holding arm or arms, until they are extended with the storm sash in open position, project in the line of the lower window sash and consequently the lower sash must be raised a considerable distance before opening 45 the storm sash. Such devices often interfere with furniture adjacent the inside of the window and moreover cause considerable trouble to manipulate. With my device the toggle arms extend at all times between the 50 storm sash and the bracket preferably located in the space between the upper sash stops. The lower sash never needs to be opened widely to manipulate my device. As has been 55 stated, it is only necessary to push the storm sash outwardly, causing the toggle arms to be extended.

It will be seen from the foregoing description 60 that I have invented an extremely simple, durable and highly efficient holder for swinging sashes adapted to hold said swinging

sashes positively fastened in open position and adapted to securely hold said sash in closed and various intermediate positions between closed and open position. It also has been seen that due to the camming action of 70 the bell crank arm 12 the connection between the outer toggle arm 11 and the swinging sash, the sash will not rattle as is often the case in sash holders.

It will, of course, be understood that various changes may be made in the form, details, arrangement and proportions of the parts without departing from the scope of the invention.

What is claimed is:

1. A holding device for swinging sash comprising a pair of toggle arms, one of said arms being pivotally connected to said sash, a bracket adapted to be readily secured to a portion of a sash frame or the like, said bracket carrying a pin provided with an enlarged head, said other arm having adjacent one end an aperture through which the head of said pin is adapted to pass and having also a relatively narrow longitudinally extending slot 90 connecting with said aperture, a latch member pivoted to said last mentioned toggle arm having a laterally slotted free end adapted to interlock with said pin inwardly of the head thereof to retain said pin within the slotted portion of said last mentioned arm and means for holding the said latch against swinging movement.

2. A holding device for swinging sash, comprising a pair of toggle arms, one of said arms being adapted for pivotal connection with a sash, a bracket adapted to be secured to a sash frame or the like, said bracket carrying a pin provided with an enlarged head, said other arm having adjacent one end an aperture through which the head of said pin is adapted to pass, and also having a relatively narrow slot communicating with said aperture, a retaining member carried by said last mentioned toggle arm having an apertured end adapted to interlock with said pin inwardly of the head thereof to retain said pin within the slotted portion of said last mentioned arm, and means for rigidly connecting said retaining member with said last mentioned arm.

3. A holding device for swinging sash comprising a pair of toggle arms, one of said arms being adapted for pivotal connection with a sash, a bracket adapted to be secured to a portion of a sash frame or the like, said bracket carrying a pivot member adapted to be connected with one end of said other arm, retaining means carried by said last mentioned arm for fastening said pivot and said arm in pivotal connection, said retaining means including a clamping member disposed intermediately of said last mentioned arm, said clamping member carrying therewith a lug protruding from the opposite side

of said last mentioned arm, said first mentioned arm being pivoted to said last mentioned arm in such manner that its inner end projects some distance beyond the common pivot, the projecting end of said arm being slotted laterally to interlock with said lug when said arms are extended to substantial

alignement, said first mentioned arm also having a recess in one of its longitudinal edges in which said lug is disposed when said arms are ¹⁰ swung together.

In testimony whereof I affix my signature.

LEWIS ASPER.
